UNITED STATES PATENT OFFICE.

ROBERT D. MADDOX, OF THE UNITED STATES ARMY.

DRILL.

1,343,180.

Specification of Letters Patent.

Patented June 8, 1920.

Application filed December 31, 1918. Serial No. 269,099.

(FILED UNDER THE ACT OF MARCH 3, 1883, 22 STAT. L., 625.)

To all whom it may concern:

Be it known that I, ROBERT D. MADDOX, major Medical Dept., U. S. Army, a citizen of the United States, stationed at Washington, D. C., have invented an Improvement in Drills, of which the following is a specification.

The invention described herein may be used by the Government, or any of its officers or employees in prosecution of work for the Government, or by any other person in the United States, without payment of any royalty thereon.

This invention relates to drill devices, more particularly to hand operated drill devices, and commonly known as breast drills which ordinarily includes a supporting handle, a rotative drill supporting member, a plate adapted to be pressed against the person of the operator, and means for rotating the drill supporting or clutch portion of the device.

The principal object of the present invention is to provide a simply constructed device of this character whereby force may be applied longitudinally to the drill, and the drill supporting mechanism retained in position while being operated.

With this and other objects in view, the invention consists in certain novel features of construction as hereinafter shown and described and then specifically pointed out in the claims, and in the drawings illustrative of the preferred embodiment of the invention.

Figure 1 is a sectional elevation of the improved device.

Fig. 2 is a side elevation viewed at right angles to the structure shown in Fig. 1.

Fig. 3 is a detached view of the breast plate member.

The improved device comprises a tubular stock or standard 10 in which a stud 11 is rotatively supported in any suitable manner, for instance, by the coaction of an annular channel 12 in the stud to receive a stop pin 13 extending through the standard. By this means the stud is rotative in the standard and held from longitudinal movement therein.

Bearing upon the lower end of the stock 10 is an annular wear ring 15. The "chuck" is indicated as a whole at 16 and is rigidly attached to the stud 11, and surrounding the

stud between the wear ring 15, and the body 55 of the chuck is another annular wear member 17, the contiguous faces of the wear members forming seats for bearing balls 18.

Formed through the stock 10 are oppositely disposed longitudinal slots 20—21 to 60 receive the body portion 22 of a shaft, the shaft passing through the slots and threaded at one end as shown at 23 to receive a combined clamping member and handle or holder, 24.

At its ends the slot 20 is enlarged to form seats 25, and the portion of the shaft 22 opposite to the threaded part is enlarged to form a shoulder as shown at 26, to engage in the seats when the shaft is located 70 at the ends of the slots. Thus when the grip member 24 is released the shaft 22 can be moved endwise until the shoulder is free from the adjacent seat 25. Then the shaft 75 can be moved to the other ends of the slots and the member 24 rotated to draw the shaft endwise again and couple in its new position with the shoulder 26 in the other seat 25.

By this simple arrangement the shaft may 80 be adjusted longitudinally of the stock 10 a distance equal to the lengths of the slots, and firmly "locked" in position at each terminal of its adjustment by the coaction of the enlargement or shoulder 26 and the 85 seats 25.

Rigidly connected to the shaft 22—26 is a double bevel gear 27—28, the shaft having an enlarged head 29 to support the gear.

Rigidly coupled in any suitable manner to the chuck 16 is a double pinion 30—31, adapted to be alternately engaged by the gears 27 or 28 according to the position of the shaft 22—26 in its slots 20—21. Thus when the shaft 22—26 is located at one 95 end of the slots, the larger bevel gear 27 will be disposed in position to engage the pinion 31, and when the shaft is located at the other end of the slots, the smaller bevel gear will be in position to engage with the 100 bevel pinion 30. Thus two speeds may be imparted to the chuck, as will be obvious, by simply changing the adjustments of the parts as above noted.

The tubular standard 10, is extended upwardly and at its upper end is internally threaded as represented at 32 to receive a threaded rod 33 which thus be adjusted

relatively to the standard 10, and within the range of its threaded portion. Near its upper end the rod 32 is provided with a stop collar 34, and attached to the rod externally of the stop collar is a hand wheel 35 having a handle 36 to enable the screw 33 to be movably operated, if required. Formed in the center of the hub of the hand wheel is a socket 37 to receive 10 a centering and holding member indicated at 38. Engaging over the tubular member 10 is a relatively long sleeve 39 having an inturned flange 40 at the upper end to engage over the stop collar 34. The sleeve is 15 provided with a longitudinally directed guide slot 41, and the standard 10 is provided with a guide pin 42 which projects into the slot. By this means when the sleeve is adjusted longitudinally of the 20 standard it is held from rotation relatively thereto. By this simple means pressure may be applied to the drill, and the pressure continued as the drill cuts into the member which is being operated upon by 25 simply rotating the wheel 35. At the same time the drill is held in position and prevented from lateral displacement by the coaction of the sleeve and the standard. By

locating a centering device above the wheel 35, any required pressure may be applied 30 to the drill, as will be obvious.

The improved implement may be utilized as an ordinary breast drill by detaching the sleeve 39 and the screw 33, together with its attachments, and substituting therefor the 35 usual breast plate represented at 60, in Fig. 3, the latter having a threaded stud 61, to engage the threaded seat 32 of the member 10.

The improved device is simple in construction, can be inexpensively manufactured and supplied as an attachment to an ordinary breast drill, or furnished together with the breast drill, as may be preferred.

Having thus described the invention, 40 what is claimed as new is—

A drill of the class described, including a tubular stock having an internally threaded portion adapted for engagement with the threaded stud of a breast plate, a 50 threaded rod engaging the threaded portion of the stock, a guide sleeve slidable over the stock and housing the rod, means for locking the sleeve to the stock and means for rotating the rod to feed the drill.

ROBERT D. MADDOX.
